(57) **CLAIM**

The ornamental design for a rattan tub cooler, as shown and described.

DESCRIPTION

FIG. 1 is a perspective view of a rattan tub cooler showing my new design.

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof; and,

FIG. 8 is a perspective view of the rattan tub cooler wherein the lid is removed.

The rattan tub cooler has a rattan or faux rattan surface thereon. The features presented in broken lines are for environmental purposes only and form no part of the claimed design.
